UNITED STATES PATENT OFFICE

MAX SCHUL, OF BRUSSELS, BELGIUM

PROPELLER FOR VESSELS AND AIRCRAFT

Application filed August 2, 1928, Serial No. 296,973, and in Germany August 3, 1927.

This invention relates to a propeller, for use in connection with vessels and aircraft, in which the blades are arranged on a solid ring or on a plurality of such rings, or on a flexible metal band or on a plurality of such bands, which encompasses, or encompass, the hull of the vessel or the body of the aircraft wholly or partly, and is, or are, driven by the motor or engine either directly or by the intermediary of cog-wheels, friction wheels, chain-wheels, or the like.

I am aware of the fact that it has already been proposed to build vessels in which the conically shaped end portions, i. e. the bow and the stern, are connected with one another by a middle portion surrounded with a movable shell provided with screw-threads, and that it also has been already proposed to attach propeller blades to a cylindrical hub so built into the hull of the vessel that the water flows past it with a very slow speed. Furthermore, it has already been proposed to attach normal aircraft propeller blades to a ring encircling the entire body of the machine and being supported on it; and finally, it has been proposed to connect certain parts of propeller blades by arms with a shaft, the thus constituted propeller being completely immersed.

Now, in none of these known propeller designs the idea has been realized to use on a ring encompassing the hull either completely or only partly only those portions of the blade surface as propelling surfaces, the efficiency of which lies between the maximum efficiency and another efficiency which is from 3 to 5% lower, the idea starting from an ideal propeller and the middle of the appertaining shaft coinciding with the centre of said ring.

The essence of the present invention consists, therefore, therein that (starting from an ideal propeller having a shaft, the middle of which coincides with the centre of the said ring) only those surface portions are used as propelling surfaces, the efficiency of which lies between the maximum efficiency and another efficiency which is lower by from 3 to 5%. It is known that those portions of a propeller blade which lie about in the mid-

dle between the shaft and the peak of the blade have a higher efficiency than those other portions which lie at the hub and the peak. If the proportion between the diameter of the circle on which the propeller element is lying and the pitch of the blade (which is assumed to be constant) is laid out as abscissa, and if the efficiency of the propeller is laid out as ordinate, there is obtained that efficiency curve in which a distinct maximum curve exists. Theoretically, an infinitely small surface stripe on the propeller would correspond to the maximum of that efficiency curve, but with consideration of the character of that curve the invention is carried out practically in this way that also those surface portions are used, the efficiency of which lies between the maximum efficiency and that other efficiency which is from 3 to 5% less, as already stated.

Propeller blades designed according to this invention are illustrated diagrammatically and by way of example on the accompanying drawing, on which Figure 1 is a view of an ordinary propeller blade with its shaft; Figure 2 shows the efficiency of a propeller element as function of the diameter relation; Figure 3 is a front-view of a vessel provided with a rigid ring encircling the hull and provided with the best-efficiency surfaces of an ideal propeller (indicated by dotted lines); and Figure 4 is a side-view of the front half of a vessel provided with the propelling device shown in Fig. 3.

On the drawing, 1, Fig. 1, denotes an element located in the immediate proximity of the propeller shaft and having a medium diameter d^1 ; 2 denotes an element lying about in the middle portion of the blade and having a medium diameter d^2 ; and 3 denotes an element lying at the blade peak and having the medium diameter d^3 .

In Fig. 2 the proportions between the medium diameter of the elements 1, 2 and 3 and the equal pitch H are laid out as abscissæ, and the efficiencies pertaining to said elements are laid out as ordinates. It can be seen from said curve that it has a maximum about the abscissa near $\frac{d^2}{H}$. Near that maximum

the efficiency curve extends comparatively flat, viz. between limits lying about from 3 to 5% below said maximum. These proportions of the propeller, viz. of the ideal propeller indicated by dotted lines in Fig. 3, are, according to this invention, selected, and they are arranged on a ring 5 supported in any suitable manner on the hull near the bow. As the supporting means, as well as the means for rotating said ring, are known, I abstain from showing and describing these details.

6 denotes the propeller blades which correspond to those surface elements of the ideal propeller, the efficiency of which lies between the maximum efficiency and 3-5% less. Instead of only one ring two or more such rings can be provided in a certain distance from one another. The power is transmitted from the motor or engine by means of a pinion (not shown) engaging an internal toothed ring of the said ring or rings.

It is no departure from the invention if the blades, instead of being secured to a rigid ring, are affixed to a pliable or flexible metal band or to an articulated chain. In cases like these the blade surfaces, instead of rotating around the propeller shaft, can move in a straight line through the water, transversely with respect to the longitudinal axis of vessel, and instead of a pinion or the like friction wheels, chain wheels and a chain, or the like, can be used. In all cases the essence of the invention resides in making use exclusively of those blade surface portions which possess and warrant highest efficiency.

I claim:

40 A propeller for vessels and aircraft, comprising, in combination, a member adapted to be moved transversely with respect to the longitudinal axis of the hull of the vessel or the body of the aircraft, and blades attached to said member and being formed by portions of an ideal propeller, the middle of the shaft of which coincides with the centre of said member, said portions being those, the efficiency of which lies between the maximum efficiency and another efficiency which is from 3 to 5% less.

45 In testimony whereof I affix my signature.

MAX SCHUL.
